CHILD'S APRON

Gertrude M. Hovey, Kansas City, Mo.

Application September 30, 1935, Serial No. 42,852

5 Claims.

(Cl. 2—48)

This invention relates to wearing apparel and particularly aprons of the character worn by children for the purpose of protecting their garments during play or at meal times, and the primary object of the invention is to provide such an apron that will be easy to place and remove and which will have, as a part of its structure, supporting members of distinctive characteristics whereby the child may place and remove the apron itself.

One of the important aims of this invention is to provide an apron structure, having as a part thereof, unique, novel and pleasant appearing parts, all of which are related and specifically designed to insure positive placement, strength of parts and ease in disassembling the elements of the structure whereby the fabric or other material used may be laundered or otherwise cleaned.

A still further object of this invention is the provision of a child's apron, wherein is embodied unique supporting members in the form of differently colored cords that are secured to the body of the apron merely by knotting said cords; the distinctive colors of the cords employed serving the purpose of rendering it possible for the child to place the supporting members and the entire apron in the proper position upon its body without the manipulation of buttons, buckles, snaps or other types of securement that have commonly been employed in garments of this character.

With these broad objects and minor objects in mind, the invention will now be described by reference to the accompanying drawing, wherein is shown one embodiment of the invention.

In the drawing:

Figure 1 is a front view of the apron embodying this invention in the operative position on the body of the wearer.

Fig. 2 is a back view of the wearer shown in Fig. 1, illustrating the position of the supporting members forming a part of this novel apron structure.

Fig. 3 is an enlarged, plan view of the back of the apron.

Fig. 4 is a cross section of the apron, taken on line IV—IV of Fig. 3, and,

Fig. 5 is an enlarged, fragmentary, sectional view taken on line V—V of Fig. 3.

I have found that children in kindergarten and lower grades of the schools are supplied with protecting garments such as aprons during the pursuance of certain courses in their program of study and a considerable amount of time is lost because the child is unable to place an apron

on himself without assistance. It is intended that an apron embodying this invention be moved to and from the operative position after once showing the child that the supporting members of particular character or color should be placed over the head or under the arms, as the case may be, and as will be more fully hereinafter set down.

The preferred embodiment of this invention permits the creation of an apron having a single piece of material such as fabric or oilcloth, that is formed to present a main central panel 6 and a secondary panel 8, disposed along each longitudinal edge respectively of said central main panel 6. Panel 6 extends longitudinally along beyond one end of the secondary panel 8 to create a bid portion at the upper part of the apron, which has a hem 10 formed therearound at the edges thereof, as illustrated in Fig. 3. This hem 10 is of substantial width and effectively reinforces that portion of panel 6 for the purpose of receiving grommets 12 that reinforce the holes which are first formed through hem 10.

A longitudinally extending plait 14 is formed in the material making up the main part of the apron along the meeting lines of the main and secondary panels 6 and 8. This plait is of appreciable width as illustrated in Fig. 4, and is created by rebending the shorter portions of the piece of fabric upon themselves so that the lower portion of the body of the apron will flare when worn to present additional coverage. Reinforcing tape 16 is stitched to the lower outer corners of panels 8 and a continuous tape 18 is stitched to the upper portions of panels 8 and along the inner edge formed by hem 10.

A grommet 20 extends through the overlapping material forming the apron and the upper end of each plait 14 respectively. It will be observed, therefore, that grommets 12 and grommets 20 extend through two and three thicknesses respectively of the material forming the panels of the apron body. The series of grommets employed in the structure are arranged in vertical and horizontal alignment so that secondary panels 8 are free to conform to the contour of the underlying garment of the wearer.

The unique supporting members are in the form of cords or similar elements 22 and 24, the ends of which extend through grommets 12 and 20 respectively. The ends of member 22 are knotted as at 26 and the ends of cord 24 are knotted as at 28. These knots are quickly tied and untied and are effective as means for connecting the supporting members with the body of the apron. When it is desired to launder the

soiled fabric forming the apron body, these knots are merely untied and supporting members are dissociated. A slide 30 interconnects members 22 and 24 intermediate their ends so that the 5 members are held together at the back, as shown in Fig. 2. In practice, it has been found desirable to use a red cord 22 and to make cord 24 of blue material so that the child may be taught to put the apron on by telling him that red goes over 10 the head and blue under the arms. Obviously, no buttons or other fastening members are involved and when the apron is in position as illustrated, it will be comfortably held in place. If desirable, the edges of panels may be provided with decorative fringe 32 and other modifications and 15 changes of specific structure will occur to one skilled in the art.

Having thus described the invention, what is claimed as new and desired to be secured by 20 Letters Patent is:

1. An apron of the character described comprising a piece of material forming a protecting member when worn having an upper and a lower pair of holes formed therethrough adjacent one 25 end thereof; grommets reenforcing the material at the holes; a cord extending through the upper pair of holes for passing over the shoulders of the wearer having knots formed in the ends thereof to preclude accidental removal from the holes; and 30 another cord passing through the lower pair of holes for extending around the waist of the wearer having knots formed in the ends thereof to preclude accidental removal from holes, the holes of the upper pair and those of the lower 35 pair being an equal distance apart and located on vertical imaginary lines spaced inwardly from and parallel to the edges of the said material whereby panels thereof along each edge are left free.

40 2. An apron of the character described comprising a single piece of material formed to present a main central panel and a secondary panel along each longitudinal edge respectively of the said piece of material; plaits formed in the said 45 piece of material along the meeting lines of the main and secondary panels to permit flaring of the piece of material forming the panels, said main central panel extending longitudinally beyond the upper ends of said secondary panels; a 50 hem of appreciable width formed around the edges of the extended portion of said central panel; grommets secured through the hem of the extended portion and the main and secondary panels at the plaits; and supporting members extending through the said grommets.

55 3. An apron of the character described comprising a single piece of material formed to present a main central panel and a secondary panel along each longitudinal edge respectively of the 60 said piece of material; plaits formed in the said piece of material along the meeting lines of the main and secondary panels to permit flaring of the piece of material forming the panels, said main central panel extending longitudinally be-

yond the upper ends of said secondary panels; a hem of appreciable width formed around the edges of the extended portion of said central panel; grommets secured through the hem of the extended portion and the main and secondary 5 panels at the plaits; and supporting members extending through the said grommets, said supporting members comprising cords having knots formed therein and engaging the grommets at the outer face of the apron.

10 4. An apron of the character described comprising a single piece of material formed to present a main central panel and a laterally extending secondary panel along each longitudinal edge 15 respectively of the said piece of material; plaits formed in the said piece of material along the meeting lines of the main and secondary panels to permit flaring of the piece of material forming the panels, said main central panel extending longitudinally beyond the upper ends of said secondary 20 panels; grommets secured through the material, forming the main and the secondary panels at the plaits respectively; and supporting members extending through the said grommets, said grommets being disposed to present an upper 25 pair and a lower pair, the distance between the grommets of the upper pair being the same as the distance between the grommets of the lower pair, the said supporting members being an upper and a lower member having their respective ends extended through the corresponding pair of grommets and each end having a knot formed therein, the upper member adapted to extend over the shoulders of the wearer and the lower member 30 adapted to extend under the arms of the wearer.

35 5. An apron of the character described comprising a single piece of material formed to present a main central panel and a secondary panel along each longitudinal edge respectively of the said piece of material; plaits formed in the said piece of material along the meeting lines of the main and secondary panels to permit flaring of the piece of material forming the panels, said main central panel extending longitudinally beyond the upper ends of said secondary panels; a 40 hem of appreciable width formed around the edges of the extended portion of said central panel; grommets secured through the hem of the extended portion and the main and secondary 45 panels at the plaits; and supporting members extending through the said grommets, said grommets being disposed to present an upper pair and a lower pair, the said supporting members being an upper and a lower member having their respective ends extended through the corresponding 50 pair of grommets and each end having a knot formed therein, the upper member adapted to extend over the shoulders of the wearer and the lower member adapted to extend under the arms of the wearer, said supporting members having a 55 rigid slide holding them in side by side parallel relation intermediate the ends thereof.
